UNITED STATES PATENT OFFICE

MICHAEL A. DROITCOUR, OF PROVIDENCE, RHODE ISLAND, ASSIGNOR TO HARRIS-SEYBOLD-POTTER COMPANY, OF CLEVELAND, OHIO, A CORPORATION OF DELAWARE

BED-MOTION FOR PRINTING-PRESSES

Application filed November 9, 1923. Serial No. 318,136.

My invention relates generally to improved mechanism for converting rotary into reciprocatory motion, and more particularly is adapted for reciprocating the type beds of bed and cylinder printing-presses.

The objects of my invention are, among other things, to provide novel and improved means for driving a printing-press bed and reversing its movements at the end of each stroke, such reversing being attained in an easy and efficient manner without shock or jarring of the various parts whereby the press may be run at a high speed without racking same.

According to my invention, the pair of oppositely-disposed racks, stationarily attached to the bed, but in adjacent and vertically parallel planes, are operated by a pair of axially-slidable, bed-drive gears arranged in tandem, the forward gear having full size teeth and driving the bed during the printing stroke, while the other gear is slightly undercut so as not to interfere with the drive of the first gear; during the inking and return stroke the undercut gear takes control of the bed until the latter comes again into mesh with the forward, full-size drive gear.

In the preferred form of my invention, the pair of oppositely-disposed racks stationarily attached to the bed but in adjacent and vertically parallel planes are operated by a pair of axially-slidable bed drive gears, preferably arranged in tandem, the forward gear having full size teeth and driving the bed during the actual printing, while the other gear is preferably slightly undercut so as not to interfere with the drive of the first gear; during the inking and return the undercut gear takes control of the bed until the latter comes again into mesh with the forward full size drive gear. Instead of being undercut, the second gear may be arranged so as to be slightly raised and lowered away from the pitch line of the racks or may be thrown into and out of control of the bed by any suitable mechanisms, for example a clutch device, it being only essential that the forward gear has undisturbed con-

trol of the bed during the printing contact of the bed and cylinders.

By the use of tandem drive gears the length of the press may be advantageously reduced as well as the weight of the reciprocating bed, and the rotary relation of the two drive gears may be adjusted to take up any loose play in the bed movement.

A further feature is the provision of an improved air-pot and plunger mechanism for retarding the bed movements at the end of each stroke embodying an auxiliary pressure reservoir for receiving and equalizing the compressions produced by the plungers in the air-pots at the end of each bed stroke, so that the final or peak pressure is not excessive, and furthermore is longer maintained during the return stroke whereby the starting of the bed from its position at rest is facilitated.

My improvements also embody other features of novelty in machines which convert rotary into reciprocating motion whereby such machines may be made more effective and otherwise better adapted for use, all of which will be hereinafter set forth and then particularly pointed out in the appended claims.

The drawings show my invention in connection with the reciprocating bed of a two-revolution press, though it may be applied and used in machines of various types with the same advantages and results.

Of the drawings, Fig. 1 is a conventional side elevation of parts of a flat-bed printing-press embodying my improvements, partly broken away and in vertical section to show the different parts;

Fig. 2 is a plan view partly broken away and in section;

Fig. 3 is a sectional view taken on the line 3—3 of Fig. 2;

Fig. 4 is a detail end view looking from the right of Fig. 3;

Fig. 5 is an enlarged detail section taken on the line 5—5 of Fig. 2;

Fig. 6 is an enlarged detail section taken on the line 6—6 of Fig. 2; and

Fig. 7 is an enlarged side view of the upper

bed rack and drive gears during the printing stroke.

Similar numerals refer to similar parts throughout the several figures.

5 Referring more particularly to Figs. 1 and 2, the impression-cylinder 8 is journalled in side-frames 9 and 10 and the reciprocating bed 11 is supported on rollers 12 travelling in the ways 13 affixed to cross-bars 14 and 15 carried by the side-frames 9 and 10 (Fig. 2). The bed 11 is provided with the depending rack-hanger 16 (Fig. 4), to which are fastened two oppositely-disposed racks 17 and 18 arranged in parallel, but adjacent, planes, 10 so that the pair of bed drive gears 19 and 20 which are axially or laterally slidable in unison may be brought into mesh with the racks 17 and 18 alternately when the gears 19 and 20 are shifted on their carrying shafts at the 15 end of each stroke of the bed 11.

20 As shown in Fig. 7, the forward gear 19 is cut with full size teeth 21 which mesh snugly with the teeth of the upper rack 17 during the printing stroke, while the teeth 22 of the gear 20 are slightly undercut so as not to interfere with the drive of the gear 19; however during the latter part of the return stroke of the bed 11, the undercut gear 20 takes control until the bed 11 on the next forward stroke is engaged and driven by the full-size drive gear 19.

25 The gears 19 and 20 are keyed to the tubular shafts 23 and 24 respectively sleeved on their respective carrying shafts 25 and 26 fastened to the side-frame 9. The opposite ends of the shafts 23 and 24 carry the pinions 27 and 28 respectively which engage the wide-faced gear 29 fastened to the drive shaft 30 journalled in the side-frame 9 (Figs. 1 and 40 2). The shaft 30 carries the pulley 31 which is rotated by the belt 32 from any suitable source of power, as the driving motor 33.

45 The impression-cylinder 8 is rotated by the gear 34 on the cylinder-shaft, by means of the intermediate gear 35 which engages the power gear 36 on the drive shaft 30 so that the cylinder 8 makes two revolutions in one cycle of the press.

50 The gears 19 and 20 and the shafts 23 and 24 are moved laterally by the yoked shift-lever 37 having lugs 38 and 39 which engage in the grooved collars 40 and 41 respectively fastened to the tubular shafts 23 and 24. The shift-lever 37 is pinned to the rock-shaft 42 journalled in the brackets 43 and 44, and is actuated by the rock-arm 45 to which is pinned the roller 46 riding in the grooved cam 47 affixed to the cross-shaft 48. The shaft 48 is rotated by the gear 49 affixed thereto, 55 which gear 49 engages with the gear 50 fastened to the cross-shaft 51 which also carries the crank gear 52 as shown in Figs. 1 and 2. The crank gear 52 is rotated by the intermediate gear 53 which engages the drive gear 54 fast to the drive shaft 30, the crank gear 52

making three revolutions in one cycle of the press.

60 The shifting of the drive gears 19 and 20 laterally causes same alternately to engage the racks 17 and 18 fastened to the bed 11, the gears 19 and 20 engaging the upper rack 17 (Figs. 2 and 7) on the printing stroke, while such gears when shifted outwardly toward the side-frame 10 engaging the lower rack 18 on the idle or return stroke of the bed 11 as shown in Fig. 2.

65 The bed-reversing mechanism is shown in Figs. 1-4, and comprises the Scotch yoke head 55 which slides in the way 56 and is held in place by the gibbs 57. The yoke head 55 is provided with a vertical slot 58 which engages the crank-pin 59 on the crank-gear 52. Secured to the yoke-head 55 is the horizontal bar 60 having the pivoted latch 61 at its forward end with the rollers 62 adapted to travel in the cam-runway 63, such a latch 61 being raised by the cam-runway 63 to engage the latch seat 64.

70 When the last tooth of the upper rack 17 is in engagement with the gear 19, the latch 61 engages the latch seat 64 cut in the hanger 16 and holds the bed 11 while the Scotch yoke 55 and crank pin 59 causes the bed 11 to reverse at the end of its printing stroke. The rear end of the bar 60 also carries the pivoted latch 65 having rollers 66 adapted to travel in the cam-runway 67 with the latch 65, being raised by the cam-runway 65 in the same manner as the latch 61 and engaging the latch-seat 68 in the hanger 16 to hold the bed 11 75 during the reverse at the end of the return stroke.

80 The momentum of the bed 11 at the end of the strokes is taken up at each reverse by the pair of air-pots 69 fastened to the forward cross-bar 14 and the pair of air-pots 70 fastened to the rear cross-bar 15 (Figs. 1 and 2). Depending from the bed 11 are the brackets 71 to which are fastened the rods 72 having the pair of plungers 73 adapted to coact with the air-pots 69, and also the pair of plungers 74 which coact with the air-pots 70. The air-pots 69 and 70 are cross-connected by the pipes 74^a and 75 respectively to equalize the air pressure produced in each pair of air-pots, and the air-pots 69 and 70 are also connected by the pipes 76 and 77 respectively to the union 78 which is connected by the pipe 79 (Figs. 2 and 6) to the auxiliary pressure reservoir cylinder 80 secured to the lower part 85 of the press (Fig. 1). The valve 81 is slideable in the union 78 to seal the orifice of either pipe 76 or 77.

90 Referring to Fig. 2 the reservoir cylinder 80 carries the plunger 82 having the guide rod 83 sliding in the passage-way 84. The outer end of the plunger 82 carries the screw-threaded adjusting bolt 85 to which is attached the cross-bar 86 sliding on the rods 87 and 88 fastened to the cylinder 80 and tie- 95

bar 89. The compression springs 90 and 91 coiled about their respective rods 87 and 88 normally force the plunger 82 within the cylinder 80 (upwardly in Fig. 2), the tension 5 of the springs 90 and 91 being regulated by the bolt 85 to vary the distance between the outer surface of the plunger 82 and cross-bar 86.

When the air-plungers 73 and 74 enter 10 their respective air-pots 69 and 70 toward the end of the bed movements, air is compressed in the air-pots and such pressure is built up in the air pots and reservoir-cylinder 80 until the pressure in the latter is sufficient 15 to force the plunger 82 outwardly to compress the springs 90 and 91. This outward movement of the plunger 82 removes the peak pressure caused by further compression in the air-pots, the springs 90 and 91 maintaining 20 a substantial uniform pressure which extends for a longer period during the return stroke whereby the starting of the bed 11 from its position of rest is facilitated. The sealing 25 valve 81 by closing the orifice of either of the pipes 76 and 77 permits the use of only a single reservoir cylinder 80 which will alternately take care of each pair of air-pots 69 and 70 during each reverse.

A spring-pressed relief valve 92 is set on 30 the opening 93 connected to the passage way 84, while the pipes 74 and 75 are each provided with suction opened gravity valves 94 and 95 respectively which are lifted to break the vacuum in the air-pots 69 and 70 as the 35 plungers 73 and 74 are withdrawn therefrom on the return stroke of the bed 11.

The operation of my press is substantially as follows:—When the bed 11 is advanced in 40 its printing stroke, the upper rack 17 first engages the undercut gear 20 which forwards the bed until the rack 17 engages the full-size drive-gear 19 (Fig. 7). When the last tooth of the rack 17 is in the gear 19, the 45 latch 61 engages the latch-seat 64 to hold the bed 11 as the Scotch yoke 55 through the crank-pin 59 on the crank-gear 52 causes the bed to reverse, the plungers 73 entering the air-pots 69 to check or retard the bed-motion 50 with the aid of the auxiliary pressure reservoir cylinder 80 as hereinbefore described.

The yoke 55 is reciprocated by the crank-pin 59 on the gear 52, and carries the bar 60 having the latches 61 and 65 on the left and 55 right ends respectively (Fig. 3). The latch 61 engages in the latch seat 64 when the last tooth in the rack 17 is on the center line of the gear 19, and by the action of the crank-pin 59 and yoke 55 takes the bed 11 to left, 60 stop, and then returns the bed to the right in Fig. 3. During this reverse movement, the gears 19 and 20 shift to be in alinement with the rack 18, and then such gears drive the bed 11 to the right until the rack 18 is in last 65 tooth with the gear 20. Then the latch 65

engages the latch-seat 68, and by the action of the crank-pin 59 and yoke 55 takes the bed 11 to the right, stop, and then returns the bed to the left in Fig. 3. During this reverse movement the gears 19 and 20 shift to be in alinement with the rack 17 to complete the 70 cycle in which the yoke 55 and crank-pin 59 slow down, stop and reverse the bed by a true Scotch yoke action.

The normal travel of the bed 11 is longer 75 than the length of the racks 17 and 18 due to the tandem relation of the gears 19 and 20, such spaced-apart position enabling such gears always controlling the bed. During the reverse the grooved cam 47 actuates the shift-lever 37 to shift the gears 19 and 20 toward the side-frame 10 (Fig. 2) so that such gears will successively engage the lower rack 18 to drive the bed 11 on the return stroke; the latch 65 engages the latch-seat 68 to hold the bed during the reverse with the plungers 74 80 coacting with the air-pots 70 and building up air pressure therein and in the reservoir cylinder 80 as hereinbefore described. By my improved construction a much smaller 85 bed to print the same size form may be used whereby the bed-reciprocating mechanism can be built of lighter parts with a smaller amount of floor space.

The detailed structure herein shown and 90 described may be varied in construction without departing from the scope of my invention or sacrificing the advantages obtainable from its use.

I claim as my invention:

1. In a mechanical movement, a driving mechanism comprising upper and lower racks, a pair of rotating gears arranged in tandem with relation to the travel of the racks, and means for bringing said gears alternately into operation with said racks. 105

2. In a mechanical movement, a driving mechanism comprising upper and lower racks in different planes, a pair of rotating gears arranged in tandem with relation to the travel of the racks, and means for bringing said gears alternately into operation with said racks. 110

3. In a mechanical movement, a driving mechanism comprising upper and lower racks in different planes, a pair of rotating gears arranged in tandem with relation to the travel of the racks, and means for sliding said gears axially to cooperate alternately with said racks. 115

4. In a mechanical movement, a driving mechanism comprising upper and lower racks and a pair of rotating gears arranged in tandem with relation to the travel of the racks to operate the latter, each of said gears having a different toothed engagement with respect to said racks. 120

5. In a mechanical movement, a reciprocating bed, two facing racks carried by the bed, and a main driving mechanism for the bed 125

comprising a pair of rotating gears arranged in tandem with relation to the travel of the bed to successively engage each rack.

6. In a mechanical movement, a reciprocating bed, two facing racks in different planes carried by the bed, a main driving mechanism for the bed comprising a pair of rotating gears arranged in tandem with relation to the travel of the bed to successively engage each 10 rack, and means for sliding said gears axially to cooperate axially with said racks.

7. In a bed-motion for printing-presses, two facing racks carried by the bed, a pair of rotating drive gears arranged in tandem and 15 successively coacting with the racks, and means for shifting said gears in unison to alternately engage said racks.

8. In a bed-motion for printing-presses, two facing racks in different planes carried 20 by the bed, a pair of rotating drive gears arranged in tandem and successively coacting with the racks, and means for shifting said gears axially and in unison to alternately engage said racks.

25 9. In a bed-motion for printing-presses, two facing racks in different planes carried by the bed, a pair of rotating drive gears having teeth of different sizes arranged in tandem and successively coacting with the 30 racks, and means for shifting said gears axially and in unison to alternately engage said racks.

10. In combination, a reciprocating bed, having a rack for imparting movements to 35 the bed, a bed-reversing mechanism, and separate means for engaging the teeth of said rack to hold the bed at the end of each movement while said bed-reversing mechanism is in operation.

40 11. In combination, a reciprocating bed, having a rack for imparting movements to the bed, a bed-reversing mechanism, and an automatically-actuated latching-device separate from said bed-reversing mechanism for 45 releasably engaging the teeth of said rack to hold the bed at the end of each movement while said bed-reversing mechanism is in operation.

12. In combination, a reciprocating bed, 50 means for driving and reversing the bed, means for retarding the movement of the bed during the reverse, and a common means controlled by a spring for alternately equalizing the action of said retarding devices.

55 13. In combination, a reciprocating bed, means for driving and reversing the bed, means for retarding the movement of the bed during the reverse, and a common means controlled by a spring for alternately equalizing 60 the action of said retarding devices and also imparting an initial return movement to the bed.

14. In combination, a reciprocating bed, 65 means for driving and reversing the bed, means for retarding the movement of the bed

during the reverse, and a spring-controlled unitary device for alternately equalizing the action of said retarding devices and also imparting an initial return movement to the bed.

15. In combination, a reciprocating bed, 70 means for driving and reversing the bed, an air-pot-plunger mechanism for retarding the movement of the bed during the reverse, and an auxiliary air-reservoir device controlled by a variably-tensioned spring for alternately 75 equalizing the air-pressure in said air-pots and also imparting therethrough an initial return movement to the bed.

16. In combination, a reciprocating bed, 80 means for driving and reversing the bed, an air-pot-plunger mechanism for retarding the movement of the bed during the reverse, and a spring-controlled auxiliary air-reservoir device for equalizing the air-pressure in said air-pots and imparting therethrough an initial 85 return movement to the bed.

17. In a bed-motion for printing-presses, a main frame, a reciprocating bed, an air-pot mechanism for controlling the movement of the bed during reverse comprising open-ended cylinders mounted at opposite ends of said frame, plungers mounted on opposite ends of the bed and coacting with said cylinders to build up air-pressure therein, and means connecting said oppositely-disposed cylinders 95 to alternately equalize and maintain the air pressure therein from said plungers.

18. In a bed-motion for printing-presses, a main frame, a reciprocating bed, an air-pot mechanism for controlling the movement of the bed during reverse comprising open-ended cylinders mounted at opposite ends of said frame, plungers mounted on opposite ends of the bed and coacting with said cylinders to build up air-pressure therein, and a 105 spring-controlled air-reservoir connected alternately with each set of cylinders at opposite ends of the frame for equalizing and maintaining the air pressure therein from said plungers.

110 19. In a bed-motion for printing-presses, a main frame, a reciprocating bed, an air-pot mechanism for controlling the movement of the bed during reverse comprising open-ended cylinders mounted at opposite ends of said frame, plungers mounted on opposite ends of the bed and coacting with said cylinders to build up air-pressure therein, and a spring-controlled air-reservoir connected alternately with each set of cylinders at opposite ends of the frame for equalizing and maintaining the air pressure therein from said plungers and means for varying the tension of said spring in said air-reservoir.

120 20. In combination, a reciprocating bed, 125 means for driving the bed comprising a pair of rotating gears arranged in tandem with relation to the travel of the bed, a bed-reversing mechanism, two air-pot-plunger mechanisms for retarding the movement of 130

the bed during each reverse, and an auxiliary air-reservoir device selectively connected to said air-pot mechanisms for equalizing and maintaining a substantially uniform air pressure in the air-pot mechanisms and imparting therethrough an initial return movement to the bed.

21. In a bed-motion for printing-presses, a plurality of racks carried by the bed, and a plurality of drive gears rotating in the same direction for successively engaging said racks to impart motion to the bed, one of said gears having a different tooth engagement with respect to said racks when intermittently actuating the bed.

22. In a bed-motion for printing-presses, a plurality of racks carried by the bed, a drive gear intermittently engaging one of said racks to drive the bed in one direction at a constant speed, and another drive gear rotating in the same direction as said first gear and intermittently engaging one of said racks to continue the drive of the bed at the same speed and in the same direction after the bed is out of engagement with said first gear.

23. In a bed motion for printing-presses, a rack carried by the bed, and a plurality of drive gears rotating in the same direction for successively engaging said rack to impart motion to the bed, said gears having different tooth engagements with said rack.

24. In a bed motion for printing-presses, a rack carried by the bed, and a plurality of drive gears rotating in the same direction and successively engaging said rack to impart motion to the bed in the same direction.

MICHAEL A. DROITCOUR.
